C. S. HERSH & C. J. O'CONNOR.
NON-REFILLABLE BOTTLE.
APPLICATION FILED DEC. 18, 1915.

1,257,228.

Patented Feb. 19, 1918.

UNITED STATES PATENT OFFICE.

CHARLES S. HERSH AND CHRISTOPHER J. O'CONNOR, OF PHILADELPHIA, PENNSYLVANIA.

NON-REFILLABLE BOTTLE.

1,257,228.

Specification of Letters Patent.

Patented Feb. 19, 1918.

Application filed December 18, 1915. Serial No. 67,621.

To all whom it may concern:

Be it known that we, CHARLES S. HERSH and CHRISTOPHER J. O'CONNOR, citizens of the United States, residing at Philadelphia, 5 in the county of Philadelphia and State of Pennsylvania, have invented new and useful Improvements in Non-Refillable Bottles, of which the following is a specification.

This invention relates to bottles, and has 10 particular reference to the non-refillable type.

An object of the invention is to provide a bottle with mechanism for preventing the refilling thereof after the original contents 15 have been withdrawn.

A further object is to provide a bottle 20 with an attachment for rendering the bottle non-refillable, said attachment consisting of few and simple parts, which can be cheaply manufactured and easily assembled, and capable of positive operation.

The invention broadly comprises a gravity 25 valve for closing the neck of the bottle when the latter is upright, and within the valve chamber a float above the valve and a ball weight above the float, both appreciably smaller than the chamber and positively closing the valve when the bottle is upright, but the float adapted to be moved out of 30 alinement between the ball and valve when the bottle-neck is horizontal, so as to thereby prevent the bottle from being refilled by submerging it.

The invention accordingly consists in the 35 features of construction, combination of elements, and arrangement of parts which will be exemplified in the construction herein described and the scope of the application of which will be indicated in the following 40 claims:—

In the accompanying drawings, wherein is illustrated one of the preferred forms of the invention:—

Figure 1 is a fragmentary vertical sectional view of a bottle illustrating the application of a non-refillable attachment hereto.

Fig. 2 is a similar view illustrating the bottle in an inverted position.

Fig. 3 is a horizontal sectional view on the line 3—3 of Fig. 1.

Fig. 4 is a similar view on the line 4—4 of Fig. 1, and

Fig. 5 is a perspective view of the valve mechanism in separated position.

Referring more particularly to the drawings, the numeral 1 designates a bottle body formed with the usual neck 2 which is provided with an enlarged annular rim 3, formed with an annular groove 4. A head 5, preferably formed of porcelain, is superposed upon the rim 3, and is normally spaced therefrom by a washer or valve seat 6, in which is formed a central opening 7. The head 5 is further provided with a circular offset 8 and surrounding the latter and the enlarged rim 3 of the neck 2 is a metallic sleeve 9, which rigidly secures the head 5 to the bottle by having the lower end of the sleeve spun into the groove 4 on the rim and having the upper portion thereof turned horizontally upon the flat face of the offset 8. By this construction the head 5 is firmly retained upon the bottle neck and can not be removed unless the sleeve 9 is damaged to 75 such an extent that it would be noticeable to a person using the bottle.

The upper end 10 of the head 5 is closed except for an opening 11 through which the liquid passes when escaping from the bottle. 80 Within the porcelain head 5 is a valve chamber 12 in which are formed a series of spaced radially extending ribs 13. The lower ends of the ribs are beveled to enlarge the chamber 12 and to permit a gravity valve 13^a to 85 have sufficient vertical movement to open or close the opening 7 in the valve seat 6. The valve 13^a is of substantially inverted cup shaped formation and is normally held upon its seat 6 by the action of a spherical weight 14 forcing downwardly upon a cork member 15, both loose within the ribs 13 and the cork normally resting upon the valve 13^a. The upper extremities of the ribs 13 are provided with wings having 90 converging edges or faces 16 for a purpose to be presently set forth and positioned above said ribs is a baffle plate 17 having the periphery thereof formed with a plurality of openings 18 in alinement with the channels 19 between the ribs 13. It is to be understood that while the head, ribs, and baffle have been described and shown as integral, 100 it is possible to form the same in separate sections and connect them in any suitable manner. In cross-section both the ball and the cork are appreciably smaller than the space inclosed by the inner edges of the ribs, as will be seen in Fig. 4. The result is that the ball is loose within the chamber excepting when 110

- it rests on the inner edges of the wings, and the cork would be loose within the chamber excepting for means which we provide to keep it normally concentric with the valve.
- 5 These means include a convex dome 22 on the top of the valve as best seen in Fig. 5, and a concave socket 23 in the lower end of the cork normally engaging with the dome as best seen in Fig. 1; and when the cork 10 moves laterally out of its normal concentric position, it increases the distance between the dome and the weight.
- In operation, when the bottle 1 is in an upright position, the valve 13 rests upon the seat 6 and covers the port or opening 7 and is retained in this position by the action of the spherical weight 14. However, when the bottle is inverted, for instance to an angle of thirty degrees, the weight 14 drops onto 15 the wings and perhaps rests upon the baffle plate 17. This action permits the cork 15 to follow the weight and the valve 13' to open, so that the fluid contained within the bottle may escape through the port 7, around 20 the circumference of the valve 13^a and into the chamber 12, passing through the channels 19 and out of the head 5 by way of the openings 11 and 18. One of the salient features of this device resides in the rapid and positive 25 operation of the valve 13^a. It will be noted that the inclined faces 16 of the wings arrest the movement of the weight 14 until the bottle has been nearly inverted to a pouring position. After the bottle has reached 30 a certain tilted position, the weight 14 will gravitate into the conical socket formed by the inclined faces 16, thereby relieving the pressure upon the valve 13^a and permitting the same to open.
- 35 40 If a fraudulent or unscrupulous attempt should be made to refill the bottle by submerging the same when horizontal, the inflowing liquid will surround the cork member 15 which, by its buoyancy, will float upwardly and close the valve 13^a, thereby effectively preventing the bottle from being refilled. Such closure of the valve occurs usually by the then upward movement of the whole of the float or cork, so that the 45 50 concave seat or socket 23 moves out of alignment with the convex dome 22 and thereby increases the distance between the valve and the weight. As the float rises the weight falls, and when such distance is increased 55 the weight is pushed toward the wings—remembering now that the parts shown in Fig. 1 stand substantially horizontally. Any tendency to roll the weight up one of the in-

clined wings meets with resistance, and therefore the weight pushes on the float and the float (now off-center) pushes the valve to its seat. If, however, the disposition of the bottle neck should be such and the flow of liquid such that the float tilts or rises at its outer end, yet its inner end rolls or rocks where it contacts with the dome 22, and the ball weight is still pushed axially within the head. The results are practically the same if the parts are properly proportioned. The web 17 prevents the valve from being exteriorly operated. The valve is freely disposed in the valve chamber, so as to return to a closed position when an exterior pressure of fluid or some other medium is projected into the mouth end of the valve chamber, thereby preventing a practical or convenient refilling of the bottle.

It will thus be seen that there is provided mechanism in which the objects of this invention are achieved and all the advantageous features above mentioned are, among others, present. The bottle is positive in action, of few parts and simple construction. The valve mechanism can be readily formed and assembled, and the movable parts thereof are so positioned that they cannot very readily get out of order, as by binding or becoming broken.

Having thus described the invention, I claim:—

In combination with the neck of a bottle, a cylindrical casing secured upon the end of the neck thereof in end to end relation therewith and having an apertured outer end, a washer disposed between said neck and said casing and having an opening therein, an inverted hemi-spherical valve seated upon said washer and normally closing the opening therein, radial ribs extending inwardly from said casing and extending from the bottom thereof to a point adjacent the top thereof, a baffle plate seated upon the upper ends of said ribs, a float slidable loosely within said ribs and concaved on its bottom face to engage said valve, and a weight disposed on said float and an outwardly extending flange on said valve, the inner end portions of said ribs being reduced and guidably engaging the flange on said valve, to prevent lateral displacement thereof when said valve is unseated.

In testimony whereof we affix our signatures.

CHARLES S. HERSH.
CHRISTOPHER J. O'CONNOR.
